United States Patent

Des. 242,088

Patented Nov. 2, 1976

242,088

HELMET

Philip E. Durand, Hudson, Lawrence R. McManus, Lynn, and William D. Claus, Jr., Natick, Mass., assignors to the United States of America as represented by the Secretary of the Army

Filed Aug. 22, 1975, Ser. No. 606,815

Term of patent 14 years

Int. Cl. D2—03

U.S. Cl. D2—232

FIG. 1

FIG. 2

FIG. 3

FIG. 1 is a front elevational view of a helmet showing our new design;

FIG. 2 is a side elevational view thereof; and

FIG. 3 is a rear elevational view.

The side not shown is substantially like the side shown.

We claim:

The ornamental design for a helmet, as shown and described.
